UNITED STATES PATENT OFFICE.

HAROLD W. CLARK, OF ALLIANCE, OHIO, ASSIGNOR TO THE BUCKEYE JACK COMPANY,
OF ALLIANCE, OHIO.

LIFTING JACK.

Application filed December 16, 1927. Serial No. 240,365.

My invention relates to a multiple lift jack wherein a plurality of telescoping screws are used to provide for a greater lifting range than can be obtained with a single screw type 5 lifting jack.

Where balloon type of tires are used on automotive passenger cars, trucks, busses, etc., it has been found necessary to use a jack having the maximum lift in relation to the height 10 of the closed jack. It is further desirable to provide a jack where the top screw is large in diameter and securely guided by the frame so as to be strong against side strains and loads which are encountered and to provide 15 so that no vertical load is carried on the rotating gear or gear box or by means for connecting screws and preventing them from revolving.

With these and other objects in view, the 20 invention consists in certain novel features of construction and combination of parts which are hereinafter described and as shown on the following drawings:

Figure 1 is a vertical central section of one 25 form of my jack extended.

Fig. 2 is a vertical central section of same showing the jack extended.

Fig. 3 is a horizontal section of my jack taken on line A—A of Fig. 1.

30 Fig. 4 is a side view of the lower end of the sleeve.

In the particular embodiment shown in the drawings, 4 is a base on which is carried the vertical hollow frame 5 supporting at its upper portion, hollow gear box 6 which I prefer to form integrally with the frame. This gear box 6 is open at its sides so that the main rotating gear 7 can be entered through said opening. Driving pinion 8 is provided with 40 teeth meshing with teeth of gear 7. Pinion 8 is rotated by means of a suitable handle or rod 9 which I have indicated but not shown in full.

Attached to base 4 I provide an upstanding screw 10 with external threads 11. 12 is a traveling nut having internal threads 13 at its lower end which engage with the external threads 11 of screw 10. Nut 12 also is provided at its upper end with internal threads 14 which engage external threads 15 of hollow screw 16. It is essential that the direction of threading of moving screw 16 be opposite to that of stationary screw 10. It is evident that the pitch of the threads of the two screws may be the same or different if desired

and if different the screw with the greater pitch will have a greater travel for a given rotation of the driving nut 12.

Screw 16 supports at its upper end load plate or saddle 17 which is attached to screw 60 by pin 18 which permits saddle 17 to oscillate slightly to conform to the character of the load carried thereby.

Traveling nut 12 is provided with slots 19 and 20 on its outer surface which engage lugs 65 on driving gear 7 and provide means whereby the nut 12 is rotated by gear 7 and still be free to slide up and down as it is elevated or depressed by the action of the threads 13 revolving on threads 11 of the stationary 70 screw 10.

Screw 16 is held from rotating by means of telescoping sleeve 21 which is carried in nut 12 and is provided at its upper end with lugs 22 and 23 which engage keyways 24—25 cut 75 on the inside surface of upper screw 16. Now sleeve 21 is kept from rotating by the novel construction of the internal screw 10 which I make of a non-circular form. I show this screw to be hexagonal in section on my 80 drawings as in Fig. 3, but it may be of any other non-circular form which will allow the sleeve 21, which is of similar form, to telescope over screw 10 and be kept from rotating thereby. I prefer to make the lower 85 end of sleeve 21 of hexagonal shape so as to conform to the shape of screw 10. At upper end of screw 10, I provide a shoulder as at 26 to prevent disengagement of sleeve 21 from screw 10 when the jack is fully extended, or in 90 case the jack is turned up side down. It will thus be seen that since screw 10 is held rigidly to stationary base 4, it will not revolve, and will in turn by its non-circular form keep sleeve 21 from rotating, and that sleeve 21, 95 by its lugs 22 and 23 which slide in keyways in traveling screw 16, will prevent screw 16 from revolving. The rotation of nut 12, which is set up by gear 7, therefore will cause the nut to rise or fall, as the case may be, upon screw 100 10, and a corresponding rise or fall will be caused by upper hollow screw 16 moving in the upper threads of nut 12. When the jack is elevated as in Fig. 2, it will be seen that the smaller screw 10 is completely enclosed and 105 any side strains will come upon the large upper screw 16 which is firmly held by large nut 12, and the nut in turn held in frame 5.

Where the jack is depressed as in Fig. 1, the sleeve 21 telescopes down over screw 10 110

and upper large screw 16, which is hollowed out, telescopes over sleeve 21 and rests inside of traveling nut 12. The internal threads 13 at lower end of nut 12 are circular in form and to provide the necessary clearance the diameter at the base of threads 13 is slightly greater than the diameter of screw 10 over the corners of the hexagon.

I do not wish to confine my invention to the use of bevel gear and pinion for rotating the traveling nut, but I may make use of other forms of gears such as spur gears, worm and worm gears, etc. for this purpose.

It will be observed from Fig. 1 that my jack is extremely compact when depressed and that when fully extended it closely approaches the maximum theoretical height.

Having fully explained my invention, what I claim as new and desire to secure by Letters-Patent is:—

1. A jack consisting of a main frame, a lower screw secured thereto, an upper screw adapted to telescope over said lower screw when jack is depressed, a traveling nut member having threads to engage the threads of said screws, a sleeve carried in said nut, being held from turning by the lower screw and having means for preventing the upper screw from turning.

2. A jack consisting of a main frame, a lower screw secured thereto, an upper screw adapted to telescope over said lower screw when jack is depressed, a traveling nut member with internal threads engaging external threads on said screws, a non-rotating sleeve carried in said nut and a gear to rotate the nut.

3. A jack consisting of a main frame, a lower screw secured thereto and kept from turning thereby, a nut traveling on said screw, an upper screw with threads engaging the threads of the nut, a non-rotating sleeve carried by the nut, held from rotating by the lower screw and in turn keeping the upper screw from rotating, means for rotating said nut held from vertical movement by the frame.

4. A jack consisting of a stationary main frame, a lower screw secured thereto, said screw being of non-circular form, a nut traveling on said screw, an upper screw with threads engaging the threads of the nut, a sleeve carried by the nut, the lower end of said sleeve being formed to telescope over the lower screw but kept from turning by the form of said screw, projections on upper portion of said sleeve adapted to engage slots in

upper screw to keep said screw from rotating and gearing carried in the main frame to rotate the traveling nut.

5. A jack consisting of a main frame hollowed out to receive two screws, said screws having external threads of opposite hand, a traveling nut with right and left hand internal threads to engage the threads on the screws, the upper screw hollowed out to telescope over lower screw when jack is depressed, a sleeve carried in said nut and held from turning by the lower screw and provided with means to hold the upper screw from turning and means for rotating the traveling nut, said rotating means being held from vertical movement by the main frame.

6. A jack consisting of a stationary frame, an upright screw secured thereto, said screw being of a non-circular form, a nut traveling on said non-circular screw, an upper hollow screw, with threads engaging the threads of traveling nut, a sleeve carried by the nut, the sleeve arranged to telescope over stationary screw and kept from turning by the non-circular form of said screw, lugs on upper part of sleeve engaging internal keyways in hollow screw to prevent hollow screw from revolving, a driving gear having lugs engaging slots on outer portion of traveling nut and means for rotating said driving gear.

7. A lifting jack having a plurality of screws, one of which is of non-circular form and a sleeve telescoping over said non-circular screw but maintained in rotative relation thereto by conforming to the shape of said screw.

8. A lifting jack having a plurality of screws, one of which is of non-circular form, a sleeve telescoping over said circular screw but maintained in rotative relation thereto by the form of said screw, a second screw telescoping over said sleeve and means for maintaining said outer screw in rotative relation to said sleeve.

9. A lifting jack having a plurality of vertical screws, the inner screw being of non-circular form, a sleeve telescoping over said screw and by its form, maintained in rotative relation thereto, an outer screw telescoping over said sleeve and maintained in rotative relation thereto, a nut with right and left hand internal threads to engage corresponding external threads on the said screws.

In testimony whereof, I have signed this specification.

HAROLD W. CLARK.
